ADJUSTABLE WAISTBAND FOR GARMENTS

Isidore Lyons, New York, N. Y.

Application July 27, 1942, Serial No. 452,473

1. Claim. (Cl. 2—237)

This invention relates to waistband structures as applied to trousers, skirts, and like garments.

The invention relates primarily to means for providing approximate adjustment in the size of a waistband and to automatic conforming adjustment to the waist of the wearer, being characterized by its simplicity of construction, ease of use, and low manufacturing cost.

Another object of the invention is to provide a structure incorporating elastic means which may be readily removed when cleaning of the garment bearing the same, is contemplated.

More specifically, this invention contemplates the incorporation of an elastic member in the waistband of a garment, concealing said elastic member therein, providing for ready removal thereof, and including inelastic end portions on said elastic member, the latter being exposed and adapted for selective connection to different parts of the waistband, and thereby affording approximate adjustment of the size of said waistband.

The invention incorporates separable fastener means whereby the waistband sizing means are readily removable, said fastener means comprising a hookless fastener to give access to the sizing means and preferably a snap fastener for removably joining the same to the garment.

The objects of the invention will be more clearly realized from the following description of the invention, said description being founded upon the illustrated embodiment which is shown in the drawing.

In the drawing:

Fig. 1 is a rear view of the upper portion of a trouser garment incorporating features of the invention.

Fig. 2 is a fragmentary longitudinal sectional view thereof as taken on the line 2—2 of Fig. 1.

Fig. 3 is an enlarged cross-sectional view as taken on the line 3—3 of Fig. 1.

Referring now to the drawing in greater detail, a garment 5 is shown as being provided with a waistband 6. Said waistband is constructed of two plies of fabric with the upper and the lower corresponding edges of the plies being hemmed inwardly toward each other. In the present instance, the waistband 6, preferably at the rear of the garment, is provided with a flap 7 permanently secured to the upper edge of the waistband as at 8 and separably secured to the lower edge thereof as by means of a slide fastener 9. This flap has one of its edges sandwiched in between one pair of the hems of the waistband 6 with a line of stitching joining said pair of hems and the interposed flap edge. One of a pair of 55

said fastener strips is secured to the waistband adjacent the other pair of said hems, with a line of stitching joining together said last pair of hems and the slide fastener strip. The mating 5 slide fastener strip is stitched to the free longitudinal edge of the flap 7. By means of this structure, said flap may be readily opened or closed forming, in the latter instance, a channel or pocket 10.

10 According to the invention, the garment is provided with a completely separable waistband sizing member 11. In this instance said member comprises an elastic portion 12 and inelastic end portions 13, the latter being each provided with 15 at least one button-hole 14. It will be noted from Fig. 1 that the elastic portion 12, when in position, is completely concealed by the flap 7 being entirely disposed within the pocket 10, whereas the end portions 13 protrude therebeyond.

20 The waistband is preferably provided with one element 15 of a snap fastener and the elastic portion is provided with a cooperating portion 16 whereby the sizing element may be separably attached to the garment as can be well understood.

25 The mentioned button-holes 14 are arranged for selective engagement with buttons 17 and 18 sewed to the waistband as shown. A reversal of the selective engagement means may be employed, the buttons being provided on the sizing member and the button-holes on the waistband. It is understood that other means may be substituted.

The above-described garment is admirably suited to the purposes of the invention. By proper 35 selective engagement of the respective buttons 17 or 18, by the sizing member, the waistband may be approximately sized. When the garment is worn, the elastic portion is stretched causing the waistband to yieldingly hug the waist of the 40 wearer and accommodate its size to his or her movements.

The folds shown in Fig. 1 will, wholly or in part, be eliminated when the garment is worn.

The efficacy of the invention is increased by the 45 ease with which the sizing member may be removed so the garment may be cleaned without subjecting the elastic to the harmful effects of that operation. By merely raising the flap 7 and separating the fastener elements 15 and 16, said sizing member is made readily accessible.

Thus there is provided simple and effective means for obtaining a properly-fitting garment which will ease to the movements of the wearer and maintain its proper position on the body. The appearance presented by the garment is at-

tractive and neat, and suspenders, belts, etc. are unnecessary for the support thereof.

Although the invention is quite simple, it lends itself to a variety of changes within the spirit and scope of the appended claims. It is, therefore, intended that these claims be not unduly limited by the instant specific disclosure which is exemplary only.

What I claim as new and desire to secure by Letters Patent is:

In a garment, a waistband of two plies of fabric, the upper and the lower corresponding edges of the plies being hemmed inwardly toward each other, a flap having one of its edges sandwiched in between one pair of said hems, a line of stitching joining said pair of hems and the interposed flap edge, a slide fastener strip secured to the waistband adjacent the other pair of said hems

and a line of stitching joining together said last pair of hems, the mating slide fastener strip being stitched to the free longitudinal edge of said flap, said flap together with the underlying portion of the waistband forming a pocket, a garment-sizing member disposed within said pocket, said member having inelastic end portions and an elastic medial portion, said slide fastener serving for detachably securing the free longitudinal edge of the flap to the waistband to afford access to said elastic portion, a snap fastener for removably securing the medial portion of said garment-sizing member to said waistband within the pocket and cooperative selective fastener means for attaching to the waistband the inelastic ends of the garment-sizing member.
